(57) CLAIM

The ornamental design for a vehicle exterior, as shown and described.

DESCRIPTION

FIG. 1 is a front perspective view of a vehicle exterior showing our new design.

FIG. 2 is a left side perspective view of the vehicle exterior of FIG. 1, wherein a right side perspective view is a mirror image thereof;

FIG. 3 is a rear/left side perspective view of the vehicle exterior of FIG. 1;

FIG. 4 is a rear perspective view of the vehicle exterior of FIG. 1; and,

FIG. 5 is a rear/right side perspective view of the vehicle exterior of FIG. 1.

The broken lines showing logos, written matter and vehicle wheels are for illustrative purposes only and form no part of the claimed design.
